Primary Examiner — Michael A. Pratt

(74) Attorney, Agent, or Firm — Thorpe North & Western, LLP

(57) **CLAIM**

The ornamental design for the projectile launcher, as shown herein.

DESCRIPTION

FIG. 1 is a perspective view of a projectile launcher in accordance with our invention;

FIG. 2 is a top view thereof;

FIG. 3 is a bottom view thereof;

FIG. 4 is a side view thereof;

FIG. 5 is an opposing side view thereof;

FIG. 6 is a front view thereof; and,

FIG. 7 is a rear view thereof.

The broken lines shown in the figures are directed to environment. The broken lines form no part of the claimed design.
